UNITED STATES PATENT OFFICE.

SAMUEL E. CONDON, OF BROOKLYN, NEW YORK.

COUCH.

No. 892,405.

Specification of Letters Patent.

Patented July 7, 1908.

Application filed December 9, 1907. Serial No. 405,638.

To all whom it may concern:

Be it known that I, SAMUEL E. CONDON, a citizen of the United States, residing at Brooklyn, in the county of Kings and State 5 of New York, have invented a certain new and useful Improvement in Couches, of which the following is a specification.

The invention is an improved couch.

The object is to permit that portion of the 10 couch upon which the hips of the user in recumbent position rest, to be conveniently elevated above the portion normally receiving the lower limbs. A couch thus constructed is of especial utility for medical or 15 surgical purposes, and for invalids generally. It also enables the user while lying on his back to read in comfort, since the disposition of the body with the knees drawn up and the feet below the level of the hips allows him to 20 hold a book in proper position before the eyes, and without awkward placing of the arms.

In the accompanying drawings—Figure 1 is a section of my improved couch on the line 25 1 1 of Fig. 2. Fig. 2 is a bottom view in plan, part of the spring-supporting cross bar being broken away. Fig. 3 is a section on the line 3 3 of Fig. 2. Fig. 4 is an enlarged longitudinal section of the latch, its shaft and 30 operating lever. Fig. 5 is an end view of said lever and shaft.

Similar letters of reference indicate like parts.

A is the rectangular supporting frame of 35 the couch.

B is a removable platform section formed of a frame C, which enters the frame A and is supported on longitudinal bars D secured inside the longitudinal members of frame A. 40 The upper side of the section is upholstered in the usual way.

E is a platform section formed of side members F and G and cross bars H, I, J, extending transversely between said members. 45 The bars H I are suitably arranged to form a support for the end portion K of the section E which forms a head and back rest for the user reclining thereon. The upper side of section E is also upholstered to correspond to section B, and the ends of the two sections 50 preferably closely abut, as shown in Fig. 1.

The side members F, G, of section E are hinged or pivoted to the side members of frame A. As here shown this connection 55 may consist of lugs L secured to frame A and pivots M, secured to the said side members

F, G, and entering apertures in said lugs. The hinge or pivot may be placed at about the middle of section platform E, or at the end thereof at which the head rest is formed, 60 or at any intermediate point, as desired. As here arranged the head and shoulders of the user are lowered as the hips are raised.

Extending across the frame A is a bar N, upon which bear two helical springs O, which 65 springs also abut upon the cross bar J of section E and normally tend to raise said cross bar J and so tilt the section E into inclined position, as shown in dotted lines Fig. 1. When the section E is in the position shown 70 in full lines, Fig. 1, with the upper surface coinciding with that of section B, said springs are compressed.

Extending across the frame A and journaled in openings in its side members is a 75 shaft P having a squared portion outside of said frame and a threaded portion at its extremities. Fast upon said shaft are two latch arms Q, each having at one edge a number of notches adapted to engage fixed 80 pins R on the side members F, G, of section E. Leaf springs S secured on bar N bear against the opposite edges of said arms Q, and tend to hold said arms in engagement with pins R. A hand lever T having a 85 squared opening may be placed upon the squared portion of shaft P on either side of the couch, and when so placed may be secured by a nut U applied to the threaded extremity of the shaft. 90

The operation is as follows; The sections B and E are normally in the position shown in full lines in Fig. 1, the springs O being compressed and the section E being held down against the resiliency of the springs by the 95 engagement of the lower notches in arms Q with the pins R. When it is desired to elevate the abutting end of section E, the shaft P is turned by means of the lever T, so as to draw back the latch arms Q against the action of their leaf springs S, thus releasing the pins R and permitting the springs O to raise said end and tilt the section into the position shown in dotted lines, Fig. 1. In case it is desired not to elevate the end of the section 100 so much, any one of the upper notches in arms Q may be caused to engage with the pins R, which is done by pushing down on the elevated end of the section until the pins R come opposite the proper notch when the 105 hand lever is released permitting the leaf springs S to throw said notch into engage- 110

ment. In like manner by depressing the end of the section until pins R come opposite the lowest notch in arms Q, the section E can be brought back to normal or level position.

5 For medical purposes foot rests V may be secured if desired on opposite sides of frame A, and the section B being removable permits the physician or surgeon to place himself inside said frame A while examining or 10 operating upon the patient.

I claim:

The combination of a frame, two platform sections thereon with their ends abutting, a hinge connection between one of said sec-

tions and said frame, a shaft extending 15 across said frame, a notched latch arm on said shaft, a stop pin on said hinged section, a spring bearing on said latch arm to hold the same in engagement with said pin, and means on the exterior of said frame for rotating said shaft to operate said latch arm.

In testimony whereof I have affixed my signature in presence of two witnesses.

SAMUEL E. CONDON.
